ZOOM OR FOCUS CONTROL KNOB FOR BINOCULAR

Claus O. Huckenbeck, Sherman Oaks, Calif., assignor to Bausch & Lomb Incorporated, Rochester, N.Y.

Filed Jan. 2, 1975, Ser. No. 538,088

Term of patent 14 years

Int. Cl. D16—06

U.S. CL. D16—59

FIG. 1

FIG. 3

FIG. 2

FIG. 4

FIG. 1 is a top plan view of a zoom or focus control knob for binoculars, showing my new design;

FIG. 2 is an elevation as seen in the direction of line 2—2 of FIG. 1;

FIG. 3 is an elevation as seen in the direction of line 3—3 of FIG. 1;

FIG. 4 is a perspective view of the knob.

The broken lines representing the binocular are shown for illustrative purposes only.

I claim:

The ornamental design for a zoom or focus control knob for binocular, substantially as shown and described.
